CAR BRAKE.

(Application filed Dec. 17, 1900. Renewed Oct. 16, 1901.)

(No Model.)

THE MORRIS PETERS CO., PHOTO-LITHO., WASHINGTON, D. C.

UNITED STATES PATENT OFFICE.

LOUIS T. PYOTT, OF PHILADELPHIA, PENNSYLVANIA, ASSIGNOR TO JOHN E. REYBURN, OF PHILADELPHIA, PENNSYLVANIA.

CAR-BRAKE.

SPECIFICATION forming part of Letters Patent No. 699,346, dated May 6, 1902.

Application filed December 17, 1900. Renewed October 16, 1901. Serial No. 78,867. (No model.)

To all whom it may concern:

Be it known that I, LOUIS T. PYOTT, a citizen of the United States, residing at Philadelphia, in the county of Philadelphia and State 5 of Pennsylvania, have invented certain new and useful Improvements in Car-Brakes, of which the following is a specification.

My invention relates to improvements in brakes for railway-cars, and more especially 10 for street-railway cars, and has for its object the elimination of cross brake-beams, which owing to the great amount of space taken up by motors and other appliances between the 15 wheels renders it extremely difficult to introduce the usual cross brake-beams and to couple them for action. I also provide a system of brake-shoes for the wheels which insures a quick stop by their immediate gripping when applied to the wheels, as the shoes 20 do not crowd the wheels away from their proper working centers or their journals out of their bearings. I also provide a double set of shoes for the wheels and a means to couple the forward shoes of each wheel to 25 each other and the back or rear shoes of each wheel to each other, and I also provide a "take-up," whereby all of the shoes on each side of the truck, and each side of the wheels, are adjusted to proper position for simultaneous 30 wheel contact, from one central point, plainly in sight, and easily accessible, by the simple turning of a nut. By employing a double set of shoes I am enabled to prolong their wear, as I present double the wearing- 35 surface and also decrease the wear on the wheel-tread by presenting the shoes upon double the surface heretofore employed, while also providing for the application of more power to stop the wheels and stop them 40 quicker, as the wheels are not pushed aside by the brake-shoes, but firmly gripped at once. By my means of side couplings for the brake-heads I also provide an additional safeguard for the prevention of persons or 45 objects passing under the wheels. The brake-shoes as arranged in my system may be applied or operated by either hand or other power.

Other features than above enumerated will 50 be pointed out in the specification.

I attain the objects of my invention by the means illustrated in the accompanying drawings, in which—

Figure 1 is a side elevation of a truck with my system of brake-shoes applied. Fig. 2 is 55 a half plan or top view of Fig. 1. Fig. 3 is an enlarged view in elevation of the brake heads and shoes and their operative mechanism more in detail. Fig. 4 is a plan or top view of Fig. 3. Fig. 5 is an edge view of the hangers 60 for the outer shoes. Fig. 6 is a modification.

Similar figures of reference indicate similar parts throughout the views.

There are many forms of trucks now in use on which my system of double brake-shoes 65 can be applied with minor modifications of hangings or suspensions adapted to the different constructions. Therefore I deem the drawings illustrating my invention as here presented will be a sufficient guide for those 70 using trucks to obtain a clear understanding as to the application to other forms and constructions of trucks.

The truck-frame 1 is one of the well-known constructions in present use and has a pair 75 of wheels 2 and a pair of wheels 3. To the front of wheels 2 are applied brake-heads 4, having removable shoes 5. To the front of wheels 3 are applied brake-heads 6, having removable shoes 7. Head 4 is suspended by hanger 80 8, carried by bracket 9, on cross-framing 10, pin 11 being inserted through bracket 9 and hanger 8 and pin 12 being inserted through hanger 8 and head 4. Head 6 is similarly supported by pins 13 14 and hangers 15 to 85 bracket 16, secured to frame 1, and the heads 4 6 of each side of the truck are secured to each other by longitudinal bars 17, running between the wheels and frame, (shown as of T-section,) held by rivets or bolts 18 in head 90 6 and 19 in head 4, and to insure the heads being correctly adjusted for simultaneous bearing on the wheels the bolts or rivets 19 pass through slotted holes 20, and bar 17 is turned inwardly at a right angle and passes 95 across the front of head 4 and is provided with an adjusting-screw 21, having a check-nut 22 in order to facilitate such adjustment.

To the back of front wheels 2 are applied 100 brake-heads 23, having removable shoes 24,

the heads being suspended by hangers 25 to brackets 26 on frame 1, pins 27 passing through heads 23 and hangers 25 and pins 28 passing through hangers 25 and brackets 26.

5 To the back of back wheels 3 are applied brake-heads 29, having removable shoes 30 and suspended by hangers 31 to brackets 32 on cross-framing 33 pins 34 passing through heads 29 and hangers 31 and pins 35 passing through brackets 32 and hangers 31. To heads 23 29 are secured longitudinal bars 36 at each side of the truck between the wheels and frame, the bar being shown as of T-section and rigidly secured to head 23 by bolts 15 or rivets 37 and adjustably to head 29 by rivets or bolts 38 in slotted holes 39, while the outer end of bar 36 is turned to pass back of head 29 and is provided with an adjusting-screw 40, having a check-nut 41 to insure simultaneous bearing of the shoes on the wheels.

It will be seen that the longitudinal bars which connect the brake-heads pass outside of the wheels, and thus form a guard as well as a brake connection, and that bar 17 is 25 above and clear of bar 36, and that the bars overreach at the center of the truck. By applying the brake-shoes both front and back of each wheel the shoes quickly grip the wheel, as the shoes do not shove the wheel and take 30 up the lost motion of bearings, boxes, pedestals, &c., before they grip the wheel, but take hold at once and at double the amount of wheel and brake surface of the systems having one shoe to a wheel, and therefore reduce 35 both the wheel-tread and brake-shoe wear to a minimum.

The method of applying the brake is by a toggle mechanism, (best seen in Figs. 3, 4,) the means being between each pair of wheels 40 at each side of the truck, where a rod 42 is placed vertically, and at its upper end has thereto attached a lever 43, to which the braking power is attached, the lever being fulcrumed on the frame at any suitable or 45 convenient point. In this instance it is fulcrumed on pin 14 of bracket 16. The rod 42 has a head 44, to which lever 43 is attached, and below head 44 a cross-head 45 is attached, (or it may be formed as a part of rod 42,) and 50 thereto are attached links 46 47 by pins 48 49. Links 46 47 pass downward and are attached to the inner ends of push-bars 50 51 by pins 52 53, the outer ends of the push-bars being attached to brake-heads 6 23 by pins 54 55, so that when rod 42 is pulled up the push-bars are forced up at their inner ends, and 55 heads 6 23, with their attached shoes, are forced to the wheels, and by means of the longitudinal connecting-bars 17 36 the heads 4 60 29 are simultaneously moved to the wheels, head 4 being moved by head 6 and head 29 being moved by head 23, so that all the heads move in unison to the wheels and grip them at the same time. If desirable and where the 65 motors and other mechanism usually placed between the wheels will permit of so doing,

tie-bars may be placed transversely from head to head or from the longitudinal connecting-bars on one side of the truck to those on the other side.

In order to be sure that all brake-shoes have the same clearance from the wheels, so they will take hold of the wheels at the same time, I introduce a take-up, which after the end adjustments are made, in the first instance by screws 21 40, will thereafter adjust any wear of the shoes, and I do this by placing a block 56 on rod 42 between the inner ends of push-bars 52 53, the block having oppositely-tapered sides 57 58, which bear 80 against the push-bar ends, and by means of a screw-thread on the lower end of rod 42 and a nut 59 and lock-nut 60 the block is moved up, and its taper takes up the wear on all shoes alike.

In Fig. 5 I show an edge view of hangers 8 31, they being closed at the top or upper end 61, and legs 62 63 are pierced with holes 64 65 to receive pins 12 34 and 11 35. With this construction the pins are relieved from 90 twisting strains, such as are produced when separate links or hangers are used.

In Fig. 6 I show a modification wherein spring-links are used instead of the rigid links 46 47, heretofore described. Head 44' is round- 95 ed at its top, and passing over it and attached by screws 66 is a double spring-lifter 67, passing down at the front and back of rod 42', and lower ends 68 69 are turned to pass over the pins in the jaws of push-bars 50' 51'. By this 100 construction I save many joints and get the advantage of the automatic return of spring-lifts 67 to their normal position after being released from action. Block 56', nut 59', and lock-nut 60' act in the same manner as heretofore described to take up the shoe wear.

I claim—

1. In a brake, a truck-frame, wheels supporting the truck, brake heads and shoes front and back of each wheel, the front heads of each wheel, and the back heads of each wheel being attached to longitudinal bars, and all the heads and shoes for each side of the truck being actuated by toggle mechanism from one point, between the wheels.

2. In a brake, a truck-frame, wheels for the truck, brake heads and shoes at the front of each wheel, longitudinal bars connecting the brake-heads; brake heads and shoes at the back of each wheel, longitudinal bars connecting the brake-heads, and toggle means located between the wheels at each side of the truck to simultaneously force the front and back shoes to the wheels.

3. In a brake, a truck-frame and wheels, 125 brake heads and shoes front and back of each wheel, the front heads of each wheel on each side of the truck being connected by a longitudinal bar placed outside of the wheels; the back heads on each wheel on each side of the 130 truck being connected by a longitudinal bar, placed outside of the wheels, and means to

operate the front and back heads of each side to simultaneously move to and press the wheels.

4. In a brake, a truck-frame and wheels, 5 brake heads and shoes at the front and back of each wheel, the heads and shoes at the front of the wheels, on each side of the truck, being longitudinally connected by a bar outside of the wheels, which is rigidly attached to one 10 head and is adjustably attached to the other head; the heads and shoes at the back of the wheels, on each side of the truck, being longitudinally connected by a bar outside of the wheels, which is rigidly attached to one head 15 and is adjustably attached to the other head; and means operative at each side of the truck to force all of the shoes at that side to the wheels simultaneously.

5. In a brake, a truck-frame and wheels, 20 brake heads and shoes for each side of each wheel, and toggle means to simultaneously press the front heads and shoes and the back heads and shoes to the wheels, for operative contact.

25 6. In a brake, a truck-frame and wheels, heads and shoes for the wheels, at the front and back of each wheel, a longitudinal tie-bar connecting the front heads and shoes of each side of the truck, the bars being located outside 30 of the wheels; a longitudinal tie-bar connecting the back heads and shoes of each side of the truck, the bars being located outside of the wheels; the tie-bars for the front heads and shoes and the tie-bars for the back heads 35 and shoes overreaching each other at the side center of the truck, and toggle means at each

side center of the truck having compression members thereto and to the brake-heads between the wheels, whereby all the heads and shoes are pressed to contact with all the 40 wheels, at the same time, by said centrally-located toggle means.

7. In a brake, a truck-frame and wheels, a toggle mechanism at the center of each side of the truck, means to connect the toggle 45 mechanism to operate brake heads and shoes at each side of the wheels, on each side of the truck simultaneously, and adjusting means on the toggles whereby the wear on the shoes is taken up by a single operation. 50

8. In a brake-toggle, a pull-bar, push-bars extending outward and connected to brake-heads at their outer ends, and at their inner ends resilient lifting-links connected thereto, reaching therefrom and connected and attached to the head or upper end of the pull-bar aforesaid. 55

9. In a brake, a truck-frame, wheels therefor, brake heads and shoes for the wheels, and hangers for the heads having substantially 60 parallel members having means for connections to the brake-head, at their lower ends, means for connection to a supporting-bracket, and thereafter united above said bracket-supporting point. 65

In testimony whereof I affix my signature in presence of two witnesses.
